UNITED STATES PATENT OFFICE.

PIETER HENDRIK VERBEEK, OF HERRNHUT, GERMANY.

DESIGN FOR A LANTERN-BODY.

SPECIFICATION forming part of Design No. 33,074, dated August 14, 1900.

Application filed March 25, 1899. Serial No. 710,509. Term of patent 14 years.

To all whom it may concern:

Be it known that I, PIETER HENDRIK VERBEEK, merchant, a subject of the German Emperor, and a resident of Herrnhut, near Lobaü, Kingdom of Saxony, Germany, have invented and produced a certain new and original Design for Lantern-Bodies, of which the following is a specification, reference being had to the accompanying drawings, forming part thereof.

The object of this invention is to produce a new and original design for lantern-bodies, and such body consists of a frame of the shape shown in the drawings, having eighteen square and eight triangular openings.

The accompanying drawings illustrate a lantern-body for illuminating devices of the kind above referred to.

Figure 1 is a view of such lantern-body in elevation, and Fig. 2 is a view thereof in perspective.

Such lamp-body is of the form shown, having eight triangular and eighteen rectangular openings, as shown in Fig. 2.

Having now described my invention, what I claim is—

The design for a lantern-body, as herein shown and described.

Signed by me at Zittau, Saxony, German Empire, this 25th day of February, 1899.

PIETER HENDRIK VERBEEK. [L. S.]
